AUTOMATIC MATERIAL WORKING MACHINE

Thomas L. Hallenbeck, George E. Hallenbeck, and Lawrence D. Ninneman, Toledo, Ohio; Thomas L. Hallenbeck, executor of the estate of George E. Hallenbeck, deceased, assignors to Baker Brothers, Inc., Toledo, Ohio, a corporation of California

Application July 16, 1953, Serial No. 368,418

9 Claims. (Cl. 29—38)

This invention relates to an automatic or semi-automatic material working or forming machine. More particularly, it deals with such a machine for forming articles directly from bars of stock by first clamping a length from the end of such a bar, cutting off said length and maintaining said clamping during all subsequent forming operations before releasing said length. Furthermore, this invention includes such a machine for simultaneously and automatically carrying out these operations on a plurality of bars of stock, such as for example a machine for making simultaneously a plurality of hollow wrist pins for internal combustion engine pistons from an equal plurality of solid bars of stock automatically fed into the machine.

Previously, automatic screw machines have been produced for operating on a plurality of articles at the time in which a bundle of bars of stock is rotated by a plurality of fixed work stations, but in such devices the tools work on the stock only from one end of the bars and the articles are cut off after the forming operations are completed. It is also known to cut off blanks from bars of stock which blanks are fed into a hopper and then automatically clamped into a trunnion wheel of an automatic screw machine in which the cutting tools may operate on both ends of the blanks at the same time.

It is an object of this invention to combine into one automatic machine the steps of cutting off the stock from the bars and operating on both ends of the blanks so cut off by gripping or clamping the blanks before they are cut from the bars of stock and maintaining this grip or clamp on said blanks for all subsequent machining operations.

Another object is to produce such a machine in which a plurality of bars of stock may be fed into different equally spaced starting work stations around a closed cyclic path of a plurality of groups of similar work stations, so that a plurality of blanks can be given a plurality of machining operations simultaneously.

Another object is to produce such a machine in which a plurality of bars are fed at each of a plurality of starting work stations.

Another object is to produce such a machine which will automatically detect the end of a bar of stock fed into it to either stop its operation or to automatically or semi-automatically feed a new bar into the machine from a magazine, and crop off its end to insure a clean cut off end on the bar before continuing again its automatic operation on the bar.

Another object is to produce a machine which may automatically operate on bars of the same or different lengths and detect the end of each bar to set up a different set of operations for stopping the machine and/or cropping the end of the subsequent bars to be fed into the machine.

Another object is to produce such a machine in which the article to be produced is chucked only once for all the operations performed in the machine.

Another object is to produce such a machine which

2

saws off one blank from a bar of stock while subsequent blanks in the machine are being machined at different successive operating stations in the machine.

Another object is to produce such a machine having automatic electric and hydraulic control devices for feeding the bars of stock into the machine.

Another object is to produce unique relatively small fixed chucks or clamping devices which hold the articles to be machined, both for severing them from their bars of stock and for all subsequent machining operations which may be to either or both ends of the articles at the same time.

Another object is to produce such a machine in which the chucks for clamping the articles are intermittently indexed to and locked at successive operating stations equally spaced around a closed cyclic path.

Another object is to produce such a machine with a plurality of machining tools all of which operate simultaneously, but in which one or more may have a greater speed of traverse during a given period of time than that of the other machining tools, such as for example an accelerated reamer in comparison to drills, facers, chamferers, etc.

Generally speaking, the machine of this invention comprises a plurality of working stations sequentially and equally spaced along a cyclic path, such as for example being equally angularly spaced around a circle. The articles to be machined are then clamped in a conveyor, such as the periphery of a trunnion wheel, which indexes to each of said stations in succession at which stations the articles are successively cut from bar stock, machined at one and/or both ends in several stages and then finally discharged from their conveyor. On either side of the indexing conveyor or trunnion wheel may be located tool cutting devices which move in unison axially to and from the trunnion wheel, with separate rotating cutting or machining tools for each of the successive working stations around the path, each time the trunnion wheel is indexed to a working station. On the reciprocating tool cutting devices there also may be provided means for increasing the forward machining motion of one or more of the tools over and above the velocity of the operation of the whole device, such as for example a reamer over a drill, facer, or chamferer.

Automatic means may be provided for longitudinally feeding substantially equal lengths of bar stock into the first working stage on the trunnion wheel. In cooperation with this feeding mechanism, there are provided around the trunnion wheel a plurality of chucks for the lengths of blanks of articles to be machined, with separate chucks for each of the working stations. Each chuck is clamped after such a length of the bar stock is fed into it and remains clamped while the length is cut from the bar, such as by a saw, and during all the machining operations until completed when it is unclamped at the last station just before indexing for a new length blank to be inserted into it. The blank or slug is thus produced in the trunnion wheel as well as machined in it.

A device also may be provided for determining the end of each bar of stock, such as by counting a predetermined number of article blank lengths which may be made after the end of the bar of stock is fed past a given point. This counter sets up a different series of automatic operations to stop the machine after the last article of the bar has been completed to further retract the feeding mechanism so that any incompletely stub end will be permitted to be discharged from the feeding mechanism, and also to set up a second sequence or crop cycle of operations. In the crop cycle only a short length of the next proceeding bar is fed into the path of the saws, so that its end will be first cropped

to form a straight flush end, before any blank lengths are fed into the machine.

A plurality of similar groups of a plurality of different work stations may be equally spaced in sequence around the cyclic path so that more than one first work station is provided for operating on a plurality of bars of stock equal to the plurality of said groups simultaneously, whereby an equal plurality of articles is formed during each reciprocating motion of the tool devices and each indexing of the trunnion wheel.

In the following description the cutting tools which have a greater velocity of advance than those of the other cutting tools in the machine will be referred to as "accelerated" tools, which is an accepted term in the art for such tools on automatic machines.

In order to explain the functions and operations of the machine of the present invention, reference will now be had in detail to a specific form of this invention for an automatic machine for simultaneously completing four hollow piston wrist pins for internal combustion engines from solid bars of steel stock, each time its trunnion wheel is indexed except in the crop cycle position. The operations performed in this machine include sawing off the blanks from the bars, facing, drilling, chamfering and reaming the blanks to form the wrist pins. The description of this machine will be divided in the following chapters and sub-chapters:

A. General Features

1. Base and arrangement of parts

B. Bar Stock Feeding Mechanisms

2. Magazine feeder

3. Roll feeder

4. Grip feeder and counter

C. Trunnion Wheel Assembly

5. Trunnion wheel mounting and drive

6. Trunnion wheel fixture chucks

D. Machining Operations

7. Stock stops and sawing mechanisms

8. Multiple cutting tool devices

(a) Drills and facers

(b) Accelerated reamers

(c) Article ejectors

E. Control Systems

9. Hydraulic systems

10. Electrically controlled sequence operations

(a) Crop cycle

(b) Automatic machining cycle

The reference characters of the parts corresponding to each of these chapters will contain hundreds digits similar to the Arabic numbers of the above sub-chapters for purposes of convenience.

The above mentioned and other features and objects of this invention and the manner of attaining them are given more specific disclosure in the following description of embodiments of this invention taken in conjunction with the accompanying drawings, wherein:

Fig. 1 is a plan view of an assembled automatic hollow wrist pin producing machine incorporating the features of this invention;

Fig. 23 is a perspective face view of the left hand cutting tool device shown in Figs. 1 and 2 mounted on its slides;

55 Fig. 24 is a schematic strip diagram of one group of the different operating or working stages or stations around half of the trunnion wheel of the machine shown in Figs. 1—3;

Fig. 25 is schematic sectional diagram showing the 60 operations performed with the tools engaged to their full depths in making wrist pins according to the stages shown in Fig. 24;

Fig. 26 is a sectional showing of a modified form of cutting tools for combining the first two operating stages shown in Fig. 25;

65 Fig. 27 is a side elevation of the device for accelerating the advance of one of the tools, namely the reamers, mounted on the right-hand tool device shown in Fig. 2 in cooperation with an edge portion of the trunnion wheel, as well as part of the means for ejecting the completed products;

Fig. 28 is a side elevation with parts broken away of substantially only the ejecting mechanism slightly enlarged from that shown in Fig. 27;

70 Fig. 29 is an enlarged rear end view of the right-hand

tool cutting devices shown in Fig. 2, showing the location and end views of the two ejecting mechanisms as shown in Fig. 28;

Fig. 30 is a schematic diagram of the hydraulic system for controlling part of the movements of the bar stock feeding mechanisms, locking the trunnion wheel and the clamping of one of the chucks on the trunnion wheel;

Fig. 31 is a schematic diagram of another hydraulic system for operating some of the movements of the grip feeder mechanism, clamping of the other chuck on the trunnion wheel, and the unclamping of said chucks;

Fig. 32 is a schematic diagram of the hydraulic system for the accelerating movement of the reamers on the right-hand cutting tool device shown in Figs. 1, 2 and 27;

Fig. 33 is a schematic diagram of an hydraulic system for moving the cutting tool devices and sawing mechanisms;

Fig. 34 is a schematic flow diagram of the operations which may be performed automatically or semi-automatically during the crop cycle for the machine of this invention, that is, to start the machine with a new bar of stock; and

Fig. 35 is a schematic flow diagram similar to Fig. 34 which shows the sequence of automatic operations of the machine of this invention when a bar is being fed into and used up in the machine, and how these operations may be interrupted and restarted or carried out semi-automatically.

A. GENERAL FEATURES

1. Base and arrangement of parts

Referring to Figs. 1, 2, and 3, the specific embodiment of the machine of this invention disclosed herewith is for producing two wrist pins at a time in each of two groups of machine operating stages, which groups are arranged in successive semi-circular paths around an indexing and rotating trunnion wheel 500 located at substantially the center of the machine shown in these figures. The plan view of the machine shown in Fig. 1 discloses a cross-shaped base having five portions, namely a central rectangular portion 100, equally extending side arm portions 101 and 102, and different length longitudinal end arm portions 103 and 104, upon all four of which arm portions cutting tools reciprocate or slide toward and away from the trunnion wheel 500 mounted on the central portion 100. In this trunnion wheel 500 the chucks 600 are mounted for holding the rod blanks which are operated upon by the multiple cutting tools each time the wheel is indexed to another position or working station. The axis of the trunnion wheel 50 is located longitudinally to the longer arm portions 103 and 104 of the cross-shaped frame, which axis is supported above the central base portion 100 by two vertical parallel tool guide and supporting plates 510 and 511, adjacent to each of which the trunnion ends of the wheel 500 are journalled. Mounted on top of these plates 510 and 511 there is located, at a slight angle from the vertical, the driving and indexing control mechanism 550 for the trunnion wheel including a separate driving motor 551 therefor.

Mounted on the shorter arm lengthwise of the machine may be a pair of cylindrical slide bars 113 along which the reciprocating cutting tool device 801 slides toward and away from the trunnion wheel 500 each time the trunnion wheel is indexed. Its approach to the trunnion wheel is at first relatively rapid over a relatively longer distance and when all the rotating drills and cutting tools are ready to contact the article to be machined, the whole device 801 is then slowly moved forward for a relative shorter distance during the cutting of the articles, after which it is again retracted at a relatively rapid rate again into the position shown in Fig. 1. The forward position of this tool device 801 is shown in dotted lines at 803 in Fig. 2. Mounted on the device 801 and behind the multiple tool head 805 is a gear box 807 which is driven by a motor 809 which

operates all of the rotary cutting tools on the head 805 simultaneously.

Similarly, mounted on the longer arm 104 of the base may be a pair of cylindrical slide bars 114 along which the reciprocating cutting tool device 800 (similar to the device 801) slides toward and away from the trunnion wheel 500, first approaching it at a fast speed and then during the cutting operation approaching further at a slower speed, and then retracting into the position shown in Fig. 1. The forward position of this tool device is shown in dotted lines at 802 in Fig. 2. Similarly to the device 801 this tool device 800 has a tool mounting head 804 in which a plurality of rotating tools are driven through a common gear box 806 by a separate motor 808, all mounted on the slides 114.

On each of the side arms 101 and 102 of the base of the machine may be mounted slides 121 and 122 upon which the cutting-off or sawing mechanisms 700 and 701 reciprocate, carrying their own separate motors 702 and 703 and separate rotating saws 704 and 705, respectively, toward and from the first stations #1 of each of the two groups of working stations provided around the trunnion wheel 500 each time the trunnion wheel is indexed. When these saws are in their full forward positions they overlap the peripheral edge of the trunnion wheel 500, as shown in Fig. 1 and in the dotted line positions shown in Figs. 3 and 13, in order to completely cut-off the ends of the bars of stock 155 fed to the trunnion wheel from along the sides of the longer base portion 104.

Along the opposite sides of, and attached to this portion 104, there may be provided the bar stock feeding devices consisting of the magazine feeders 200 and 201, roll feeders 300 and 301, and grip feeders 400 and 401. The magazine and its feeders 200 and 201 may be supported above the base portion 104 by brackets 130 and 131, and an extra floor bracket 132 (see Fig. 4) may be placed beyond the end of the machine to support the outer ends of the bars 150 in the magazine. The roll feeders 300 and 301 may be supported at the outer end of the base portion 104 on a common stand 135, and the grip feeders 400 and 401 may be supported by brackets 136 and 137 near the inner end of the base portion 104. Since the length of the bars 150 which are fed into the machine are preferably longer than the longest arm portion 104 of the base of the machine, and the longer the bars the longer the uninterrupted continuous operation of the machine between crop cycles, the roll feeders should be placed not farther from the grip feeders than they are from the outer ends of the bars 150.

The magazine feeders separately feed pairs of the bars 150 into each of two roller feeders which in turn feed those bars from positions 153 to the two grip feeders, which then feed the bars from the positions 155 to the first working stations #1 at the trunnion wheel 500. The magazine feeders may select the bars 150 (see Fig. 4) from parallel rows of bars set up between inclined bar guiding supporting strips 156, 157 and 158 projecting upwardly and outwardly from each side of the base portion 104.

Beneath the trunnion wheel 500 and longitudinally across the side arms 101 and 102 inside the base, may be provided a conveyor, such as a shaker conveyor 160 (see Figs. 2 and 3) for removing the chips and shavings, etc. which are cut from the bars and bar lengths by the machining and cutting tools. In Fig. 2 the trough 161 of the conveyor 160 is shown to be fed by material collecting and deflecting plates 162. One end of the shaker conveyor shown in Fig. 3 may be provided with a motor 163 connected through gearing mechanism 164 for reciprocating the conveyor trough 161 against the action of a spring 165 located at the opposite end of the conveyor 160. The trough 161 may be open at one and at its lower end, shown at the left in Fig. 3, to feed into any hopper or other conveyor (not shown) for removing the chips to a baler or the like, as desired.

At the end of each group of stations, or the last stations #9 on the trunnion wheel, the completed blanks or articles 850 formed in the machine may be ejected into guide channels, such as 166 shown in Fig. 2, which direct the pieces into chutes 167 for removal out through an opening 168 in a side of the base portion 103; there being similar channels 166 and chutes 167 on each side of the base extension 103, for each of the two opposite discharging stations #9 around the trunnion wheel.

Attached to, but preferably located off from the machine at its outer corners are separate hydraulic pump and motor units, which may be mounted on their liquid reservoirs, and may be employed for operating the sliding movements, feeding mechanisms, locking mechanisms, etc. employed in the machine. For example, referring to Fig. 1, motors 170 and 171 which drive hydraulic pumps 172 and 173, respectively, may be employed for operating the hydraulic cylinders 174 and 175 which move under the control of electrically operated hydraulic valves, for effecting the two forward and one retracting movements for the tool devices 800 and 801, respectively, as will be described later in chapter 9 and Fig. 33.

The motors 180 and 181 driving hydraulic pumps 182 and 183, shown at the end of the base portions 101 and 102, respectively, may be employed for operating hydraulic cylinders under the slides 121 and 122 for reciprocating the cutting-off mechanisms 700 and 701, respectively. These separate hydraulic systems may also be under the control of electrically operated hydraulic valves, which will move them similarly to that of the tool devices 800 and 801, as will also be described later in chapter 9 and Fig. 33.

The two additional motors 190 and 191, also located at the ends of the base portions 101 and 102, respectively, may be provided for driving the hydraulic pumps 192 and 193, respectively, and may be employed for operating the bar feeding and clamping mechanism through a plurality of separate hydraulic cylinders and their separate electrically controlled valves, as will be described later in sub-chapter 9 and Figs. 30 and 31.

The other additional motor 194 at the end of the base member 104 driving hydraulic pump 195, may be provided for operating the automatic accelerating tool mechanisms mounted on the tool device 800, as will be more specifically described later in chapters 8b and 9 as shown in Fig. 33.

The purpose of mounting these hydraulic pump and motor units at the corners of the machine is to remove them from the working center of the machine around the base portion 103, so that easy access can be had to the machining and machined parts in case chips get jammed in them, or the like, without having to climb over these motors. This location also keeps the motors away from the cooling cutting liquid which is continuously circulated through the machine during its operation. Furthermore it enables the separate pump units and their hydraulic liquids to be kept cooler and more accessible for repairs.

The automatic control for the machine may be provided in a separate cabinet or cabinets, one of which may be located at 196 as shown in Fig. 1, adjacent which panel an operator for the machine may be positioned and upon which panel may be provided the manual control buttons for stopping and performing any one of the operations manually, as will be described later in sub-chapter 10 in cooperation with the switches and buttons disclosed in the electrically controlled flow diagrams of Figs. 34 and 35. Another and larger cabinet 197, which may contain all of the electrical switches, relays, timers, etc., may be located further away from the machine and connected to the cabinet 196 through a bundle of electrical conductors 198 and connected to an electric current supply through conductors 199.

B. BAR STOCK FEEDING MECHANISMS

2. Magazine feeder

Referring now to Figs. 4, 5 and 6 there are shown more details of one of the magazine feeders 201, adjacent the middle guiding supporting strips 156, 157 and 158 adjacent the roll feeder 301, providing slots 204 and 205 for the parallel rows of bars 150 to roll and/or slide by gravity into the selector jaws 210 and 211 of the feeder. A pair of hydraulic cylinders 220 and 221 are connected to the ends of crank arms 222 and 223, respectively, the rotating axis end of which crank arms are keyed to the parallel shafts 224 and 225, which extend the length of the bar stock magazine. Adjacent each of the guiding strips of the magazine, there may be keyed to these shafts the selecting jaws or cams 210 and 211 (see Figs. 5 and 6). Thus, when the cylinders 220 and/or 221 are operated, either automatically or manually, the cut-out portions 212 and 213 in the jaws 210 and 211 are rocked to feed one new bar 150 from each corresponding slot 204 and 205 to the roll feeder 301, where these selected bars rest on the idler rolls 302 and 303 (see Figs. 4, 5, 7, 8 and 9).

Now four bars 150 have been fed, either one or all at a time, into each of the four positions 153, two on each side of the machine, and are resting on the rollers 302 and 303 for the next feeding step by the roller feeders 300 and 301, to move these bars longitudinally to the grip feeders 400 and 401 and toward the periphery of the trunnion wheel 500.

3. Roll feeder

After the pairs of bars 153 have been deposited on the grooved supporting idler rollers 302 and 303, positively rotating complementarily grooved rollers 304 and 305 may then be simultaneously or individually pressed down on and frictionally engage the top of each of the bars 153 (see Figs. 7, 8, 9 and 10).

The positively driven rollers 304 and 305 are mounted at the center of L-shaped levers 310 and 311, respectively, both of which levers are freely pivoted at their adjacent ends on a common shaft 315. On one end of this shaft 315 is mounted a spur gear 320 which is driven by one of the two motors 321 through a reduction gear device 322. The gear 320 is in mesh with a pair of gears 324 and 325 which are keyed to the stub shaft 330 and 331 together with the positively driven rollers 304 and 305, respectively. Since the movement of the levers 310 and 311 is planetarily around the same pivotal axis as that of the drive gear 320, the gears 324 and 325 are always in rotation when gear 320 is rotated.

The operation of the levers 310 and 311 may be controlled by separate hydraulic cylinders 340 and 341 having pistons 342 and 343 pivoted to the outer ends of the levers 310 and 311, respectively, so that when the driven rollers 304 and 305 are to be engaged with the bars 153 to feed them longitudinally to their corresponding grip feeder 401, the pistons are operated to move the rotating rollers 304 and 305 downwardly into the positions shown in Figs. 7, 8, 9 and 10, to push the pair of bars 153, longitudinally into the position of bars 155 (see Fig. 4) whereby they abut against the extended stock stops 710 and 711 which will be described later in chapter 7 and during the cropping cycle.

After the grip feeders have taken over the feeding of the bars from their position 155, the pistons 342 and 343 may be raised, the motors 321 may be stopped and the stock stops retracted, so that the bars will be only under the control of the grip feeders and free to roll on their supporting idler rollers 302 and 303 and other similar idler rollers as 350 and 351 (see Fig. 4) which may be provided on brackets 131 and 132. The further control of the cylinders 340 and 341 will be described in connection with the operation and the hydraulic system shown in Fig. 30 in chapters 9 and 10 which follow.

4. Grip feeder and counter

Referring first to Figs. 1 and 4, there are shown adjacent the trunnion wheel 500 and next to the saws 704 and 705 the grip feeder mechanisms 400 and 401, respectively, for feeding substantially equal lengths of bars 155 successively into the chucks 600 on the trunnion wheel 500. Each of the pair of grip feeders 400 and 401 comprises four separate hydraulic cylinders for operating this mechanism, namely the opposing pair of cylinders 410 and 411 for gripping the ends of a pair of bars 155 adjacent the trunnion wheel 500, a larger cylinder 414 or 415 for moving the gripping mechanism together with their pair of bars 155 the length substantially equivalent to the length of the blanks to be cut-off in the rotating trunnion wheel of the machine, and hydraulic cylinder 417 (see Fig. 12) which locks the grip feeder in its forward position during the cropping cycle which will be described later, that is only when the very tip end of a new bar is to be sawed off to form a smooth surfaced end before the bar is fed by stud or blank lengths into the trunnion wheel. Thus, the hydraulic cylinder 417 is only operated during the cropping cycle, as are the cylinders which operate the magazine feeders and the roll feeders described in the previous two chapters 2 and 3. The grip feeder mechanisms are supported by the base portion 100 on stationary brackets 136 and 137, and only their bar gripping parts and hydraulic cylinders 410 and 411 are moved relative to their brackets 136 and 137 by the cylinders 414 and 415. The control of these hydraulic cylinders is through electrically operated hydraulic valves under the automatic control of relays, solenoids and timers, and limit switches such as switch 412 in Fig. 12, as will be described in the system disclosed in Figs. 30, 31, 34 and 35 in chapters 9 and 10 which follow.

The bars 155 may be guided by the rollers 420 (see Fig. 11) into the apertures 424 and 425 between the fixed gripping jaws 426 and 427 and the movable gripping jaws 428 and 429, respectively (see Fig. 12). The slidably movable jaws 428 and 429 are slid toward the jaws 426 and 427 by the cam action of the beveled piston heads 430 and 431 of hydraulic cylinders 410 and 411, respectively, against rollers 432 and 433 mounted on the slides 434 and 435 carrying the jaws 428 and 429. Thus, as the pistons 436 and 437 from the cylinders 410 and 411 are forced outwardly from their cylinders toward each other as shown in Fig. 12, the sliding jaws 428 and 429 are pressed against the bars 155 inserted into apertures 424 and 425 to grip these bars by clamping them against the relatively fixed jaws 426 and 427, respectively. When the rods 155 have thus been gripped, the cylinders 414 and 415 may be energized to move the movable parts 440 and 441 of the grip feeders 400 and 401, respectively (see Fig. 4 also), carrying said cylinders 410 and 411 within their gripping jaws, along the fixed slides 442 and 443 (see Figs. 4 and 12) toward the trunnion wheel 500. The limits of the strokes of these movable parts may be adjusted by bolt 444 (see Fig. 11) to correspond substantially to the blank lengths to be inserted into the trunnion wheel 500 and sawed off by the saws 704 and 705.

The hydraulic cylinders 414 and 415 are provided with extra piston heads 464 and 465 and connections (see Fig. 31), so that they may be retracted for a distance greater than the predetermined length distance of the blanks, at the end of each bar, so that any stub end less than the length of a blank will be sufficiently clear of the jaws 426, 427, 428 and 429 after the last sawing operation to permit such a stub to be removed or to drop onto the shaker conveyor 160 without jamming the apparatus. The operation of these extra piston heads 464 and 465 of cylinders 414 and 415 will be described later in connection with Fig. 31 and the operation flow of Fig. 35.

In order to determine the rear end of bars 155, or when

a bar is used up and the machine should be prepared for the cropping cycle operation, limit switches 470 and 471 may be located at a predetermined number of blank lengths back from the saws 704 and 705 (see Fig. 4). 5 These switches 470 and 471 may comprise electrical spring loaded contacts that ride along the bars 155, and when these switches roll or slide off the rear ends of these bars, their contacts may start an electrical counter mechanism in the control cabinet 197 to count reciprocations of the grip feeders 500 corresponding to said predetermined number of blanks until the bar is used up. 10 The purpose of locating these switches 470 and 471 (similar to cam operated switch 412 in Fig. 12) at a distance back from the trunnion wheel is to prevent them 15 from being affected by the cutting and cooling liquid circulated around the trunnion wheel and by any chips or shavings which may be thrown off by the cutting tools.

Only during the cropping cycle when the front tip end of a new bar of stock is being cut-off, is the grip feeder 20 slide locking device, comprising hydraulic cylinder 417, put into operation. This cylinder 417 is then operated to lock the sliding part 441 only when it is in its forward position as shown in Fig. 11 (as distinguished from its rearward position as shown in Fig. 4) by pulling a section 25 477 (see Fig. 12) of the dove-tailed immovable part 478 of the grip feeder 441 tightly against the movable part 441 of the slide 442, to steady the movable part 441 when its grippers 426, 427, 428 and 429 are the only clamps holding the new bars 155 when the saw 705 crops off the 30 stub ends of said new bars. The grip feeder 440 is constructed and operates similarly to the grip feeder 441 just described.

C. TRUNNION WHEEL ASSEMBLY

5. Trunnion wheel drive and mounting

Referring now to Figs. 13, 14, 15, 16 and 17 there are shown details of the trunnion wheel mounting and drive mechanism, wherein the trunnion wheel 500 is mounted 40 between the guide plates 510 and 511 which are bridged across their tops by plate 515 for supporting the indexing mechanism 550 and for reinforcing the plates 510 and 511. Inside of and anchored to the plates 510 and 511 may be mounted additional parallel supporting members or plates 520 and 521 in which may be mounted the 45 roller bearings 524 and 525 which support and journal the trunnions 526 and 527, respectively, of the trunnion wheel 500. At equal radial distances from the axis of the trunnion wheel, there are located apertures or holes 530, 532 and 531, 533 circumferentially in the plates 510, 520 and 511, 521, respectively, which act as openings and guides for the reciprocating drill and cutting tools mounted on devices 800 and 801 at the working stations around the trunnion wheel. Also at equal radial positions and spaced at equal angular distances around and inside of the guide 50 holes there may be placed adjustable alignment and abutment screws 535 (see Fig. 15) having projecting hardened ends 536 which abut at each of the indexing stations of the trunnion wheel 500 with hard headed rivets 537 fastened in the sides of the trunnion wheel, to reduce wobble and axial movement of the trunnion wheel 500 when the cutting tools are operating on the blanks chucked in the trunnion wheel 500.

Mounted on one of the plate members 511 there may be mounted a radially extending drive shaft 540 which extends up at a slide angle from the vertical in order not to cover one of the apertures 531 or 533, and at a station where there is no cutting tool from that side of the trunnion wheel (see Fig. 24). This shaft 540 may have keyed to its lower end a bevel gear 541 which meshes 65 with a bevel gear 542 keyed to the trunnion 526 of the trunnion wheel 500. The outer end of the shaft 540 may be provided with a spur gear 545 in mesh with another spur gear 546 mounted on a shaft 547, parallel to shaft 540, that extends into the housing of the indexing and driving mechanism 550 which controls the rotation of the trun-

nion wheel 500 to move successively through equal angular distances corresponding to each of the working stages around the trunnion wheel.

A separate electric drive motor 551 for and mounted to the mechanism 550 may have a chain or belt drive connection 552 (see Fig. 17) with a pulley 553 which then is geared to drive the shaft 547. Mounted on the shaft 547 there may be two or more parallel cam wheels 560 and 561 provided with definitely angularly spaced cam projections 562 and 563, respectively, which contact projections to operate switches 565, 566 and 567 to control the operation and energization of the motor 551 and the definite indexing of the trunnion wheel 500. Thus, for one complete revolution of the shaft 547, the trunnion wheel 500 may be indexed from one station to the next, which in the present illustrated machine is 20° of arc. The exact degree of rotation may be insured by another cam wheel 570 mounted on shaft 547 having a notch 571 which is engaged by a pawl 572 pressed by spring 573 continuously against the outer surface of the wheel 570. When the wheel 570 rotates in the direction of the arrow and the pawl 572 falls into the notch 571, the switch 575, following the pawl 572 through lever mechanisms 576 and 577, may be operated to indicate one rotation has been completed and through one or more of the cam operated switches 565, 566 and 567, the motor 551 may be reversed to insure a positive seating of the pawl 572 in the notch 571 to stop the rotation of the shaft 547 at a definite point as shown in Fig. 17. The exact stopping point of the wheel 570 may be regulated by means 580 located outside of the housing for the mechanism 550.

In order to anchor positively the trunnion wheel 500 from turning when it is in each of its working station positions, or at each 20° of its rotation during the machining operations, there may be provided a plurality of shot pin mechanisms, such as 585, 586 and 587, which comprise separate hydraulically operated cylinders for thrusting hardened pins, as pin 588 of mechanism 585, into hardened sleeve inserts, as insert 589, located at definite angular intervals of 20° around the trunnion wheel 500. There are thus provided two shot pins 585 and 586 from the plate member 511 into one side of the trunnion wheel 500, and one shot pin mechanism 587 from the plate member 510 into the other side of the trunnion wheel, so that at each station during any machining operation, the trunnion wheel 500 is locked to both of its guide supporting plates 510 and 511 by said three shot pins, preventing any relative movement between any of the parts of the trunnion wheel or either of its two supporting plates. Thus, before each time the trunnion wheel is indexed all three of these shot pins must be withdrawn from the position shown for the mechanism 585 in Fig. 14 so that the trunnion wheel 500 may be rotated or indexed 20°, and then before any of the cutting tools are moved into their cutting positions, these same shot pins are again thrust forwardly to anchor the trunnion wheel 500. In order to indicate that the shot pin mechanisms 585, 586 and 587 are either advanced or retracted an electrical limit switch, such as switch 590 mounted on member 511 in Fig. 13, may be mechanically connected to the shot pin mechanism 586 to control the proper timing for the intermediate machining. Other electrical limit switches (not shown) may be provided for each of the shot pin mechanisms, but since all the shot pins are preferably operated in unison, one such switch 590 may be sufficient.

6. Trunnion wheel fixture chucks

Referring now to Figs. 18, 19, 20 and 21, there are disclosed in detail the chuck fixtures 600 which are located circumferentially around the periphery of the trunnion wheel 500, one clutch for each of the working stations of both groups of stations, which in the illustrated machine comprises eighteen stations and chucks spaced 20° apart, nine in each of the two groups, making up the total 360° in the circular closed path of working stations

herein provided. Since all of the chuck mechanisms are the same, only one will be described specifically.

Referring now specifically to Fig. 18, the fixture chuck or clamp for the blanks to be machined, comprises a pair of parallel fixed C-shaped jaws 601 and 603, each of which may comprise a spaced pair of hardened C-shaped inserts 605 (see Fig. 20) with hardened projections 606 spaced at an angle of about 90° apart opposite the open end of the C. A pair of these inserts 605 are spaced adjacent opposite surfaces of the trunnion wheel 500 (see sectioned part of Fig. 19) to support the bar blanks 755 at least adjacent each of their ends at two points around their circumference by the projections 606 as shown in Fig. 20. A pair of movable cooperating jaw faces 611 and 613 are provided opposite the teeth or projections 606, which faces are mounted on a nut wedging block 615 which is screwed radially toward the axis of the trunnion wheel 500 by the rotation of the stub shaft 616 upon which the nut 615 is threaded.

The angle of the wedging movable jaw faces 611 and 613 may be varied within limits, providing the perpendicular from their faces passing through the axis of the blanks 755 being clamped, also pass between the projections 606 of the stationary C-shaped jaw inserts 603. The clamping and wedging action of the movable jaw faces 611 and 613, urging the cylindrical blanks 755 against both pairs of the teeth 606 of the cooperating jaws 611 and 603, respectively, enable a tighter grip to be had on the blanks 755 for the given gripping force than can be obtained by a direct clamping action.

This stub shaft 616 may be mounted in the thrust bearings 617 and 618 on opposite sides of a pinion gear 620 keyed to the shaft 616. This pinion gear 620 meshes with a rack 621 on a slide rod 622, the end of which rod may be abutted and pushed parallel to the axis of the trunnion wheel 500 by means of properly located hydraulic piston mechanisms 630 and 631 (see Fig. 13), mounted on the guide plate 511 adjacent the two first working stations #1, to push the rack rod 622 in a direction to screw the nut block 615 inwardly to clamp the blank ends 755 in the chucks 600. An additional pair of hydraulic piston mechanisms 632 and 633 (see Fig. 16) may be mounted on the other guide plate 510 adjacent the last working stations #9, for abutting and pushing the other end of the rack rod 622 in the opposite direction to unclamp the completed blanks from the chuck fixtures. Thus, when the rack rods 622 are forced in one direction by the pressure of hydraulic piston mechanism 630 or 631, the movable block 615 remains clamped and wedged against the blanks 755 under the mechanical advantage of the wedging action of the balanced jaw surfaces 611 and 613 and of the threads on stub shaft 616 until the stub shaft 616 is rotated in the opposite direction by the action of unclamping hydraulic piston mechanism 632 or 633. Accordingly any pair of blanks 755 which are clamped in the chucks at station #1 are maintained clamped through all of the subsequent working stations and their operations until the final station #9 where they are unclamped and ejected.

The nut block 615 may be prevented from rotating by a slide guide 640 and the outer ends of the chucks may be covered with a plate 641. The chuck assemblies may be fitted into radial holes 645 (see Fig. 15) around the periphery of the trunnion wheel 500 and held in place by a pair of bolts 646 and 647 and wedges 648 between adjacent chuck assemblies. Between each of the chuck assemblies in the wheel 500 may be provided the shot pin engaging sleeves 589 previously described.

D. MACHINING OPERATIONS

7. Stock stops and saw mechanism

In order to crop off a short end of each of the new bars of stock inserted into the machine by the roller feeders 300 and 301 and not waste a full length blank of the stock, the stock stops 710 and 711 may be pro-

vided (see Figs. 4, 11, 27) which may comprise rods separately connected to hydraulic piston devices 712 and 713 which may be operated to extend or advance stops 710 and 711 (into the dotted line positions shown in Fig. 11) substantially through the openings between the jaws of the chuck 600 on the trunnion wheel 500, so as to stop the ends of the new bars 155 fed by the roll feeders just slightly beyond the cutting edge of the saws 705 or 704. Thus during this cropping cycle only the tip ends of the new bars are cut off by the saws, so as to form smooth flush ends for the first bar blanks 755 to be anchored in the chucks 600 at the next indexing of the trunnion wheel. This cropping cycle, however, does not insert blanks in the chucks 600, so during this one indexing period there is the loss in the manufacture of two pairs of articles in the trunnion wheel, because a cropping cycle corresponds to an interval of one machining operation at each of the working stations. After the cropping cycle is over, the stock stops 710 and 711 are retracted either into the position shown in Fig. 11 to act as stops for the grip feeder also, or they may be retracted still farther so that the length of the blanks is regulated only by the operation of the grip feeders 400 and 401. The stock stops thus remain retracted until a new bar is again fed toward the trunnion wheel. The advanced and retracted positions of the stock stops 710 and 711 may be separately adjusted by means of the threaded portions 714 and 715 and nuts 716 and 717 between the stop ends and the pistons of the hydraulic devices 712 and 713, to correspond to any desired cropping length which may be required depending upon how roughly cut the ends of the new bars may be.

Since during the cropping cycle the ends of the new bars 155 are only held by the grip feeder jaws 426, 427, 428 and 429 in the position shown in Fig. 11, the chuck fixture 600 is not clamped on the stub ends to be cropped or around the stock stops 710 and 711 which project through them during this cropping cycle operation.

During this cropping cycle the saw mechanisms 700 and 701, which have rotary saws 704 and 705, are moved by their respective pistons 742 and 743 into and through their cutting operations to cut through the bars 155 of stock, just as they would at any other interval or stage of operation for cutting off the proper length blanks from the bars, as occurs during the following working intervals until the bars 155 in the grip feeders have been completely sawed into proper length blanks.

8. Multiple cutting tool devices

(a) DRILLING FACES

As stated above there are shown herein nine successive operating or working stages #1 through #9 in each of two groups of stages, each of which group extends half way around the periphery of the trunnion wheel 500. Referring to Figs. 22 and 23 there are shown the face or cutting ends of the tool devices 800 and 801, respectively, with each of the nine stations numbered consecutively thereon, at each of which stations #2 through #9 on device 800 there is a pair of projecting operating tools. Since some of the operation stations provide tools only for operating from one end of the blanks, the same number of the pairs of tools for the same operating stations are not present on the face of the other and cooperating tool device 801 of Fig. 23.

For example, the operating stations for producing a hollow wrist pin from a solid bar blank 755 may be followed consecutively through stations of corresponding numbers in Figs. 24 and 25. Referring now to Fig. 24, the ends of a pair of stock bars 155 are first fed into the first station #1 where they are clamped in the trunnion wheel 500 by chucks 600, and sawed-off by the rotary saw 704 which is the only cutting tool cooperating with station #1 for which there are no cutting tools on the devices 800 or 801 shown in Figs. 22 and 23. After the blanks 755 have been produced, the trunnion wheel 500 is

indexed in station #2 where two pairs of oversized drills 810 approach the ends of the blanks 755 to center these pieces and provide the inside chamfers 811 thereon, shown on the piece 815 in Fig. 25. The piece 815 is then indexed to station #3 where another two pairs of opposing and smaller drills 820 drill holes into about $\frac{1}{4}$ of the length of the piece from each end to form the piece 821 in Fig. 25. After this operation all the drills 820 are retracted and the pieces 821 are indexed to station #4 where another two pairs of opposing drills 822, similar to drills 820 drill another $\frac{1}{4}$ of the length into each end of the pieces 821 forming articles or pieces 823 as shown in Fig. 25. Next the articles 823 are indexed to station #5, where a third two pairs of opposing drills 824, similar to drills 820 and 822 drill another $\frac{1}{4}$ of the length in from each end in the blank to form the article 825. Then in station #6 mounted on the device 800 only is a similar pair of drills 826 for which there are no cooperating drills on the opposing device 801, which drills 826 drill only through the last $\frac{1}{4}$ of the length of the blanks to produce the tubular articles 827 with holes 828 completely through them. It is through this station #6, which contains no cutting tools in Fig. 23, that the driving shaft 540 for the trunnion wheel radially projects from the axis 25 of the trunnion wheel.

Figs. 24 and 25 show that the setting for the ends of each of the drills 810, 820, 822, 824 and 826 projects slightly farther forwardly or outwardly from the faces of each of their supporting devices 800 and 801, so that 30 by moving the devices 800 and 801 the same distance forward each reciprocation, which distance is definitely determined by the abutment of devices 800 and 801 against the adjustable stops 812 and 813, respectively, (see Figs. 22 and 23), the proper depth will be cut into each article 35 at each operating station.

The next indexing station #7 comprises the combined tools 830, which face and outside chamfer both ends of the pieces 827, by again approaching the pieces 827 from both ends to produce the articles 835 to their proper length. Next the article 835 is indexed into station #8 in which the whole inside hole 828 is reamed out from only one end of the article 835, by high speed faster travelling reamers 840 to produce the completed article 850.

If desired, the operating stages 2 and 3 may be replaced by a single stage at either station #2 or #3, which may include the first $\frac{1}{4}$ drilling and the inside chamferer by a combined tool 829 shown in Fig. 26, to produce piece 821 directly from the blank 755. With the tools 829 one of the stations #2 or #3 in the cycle could be removed from each group.

(b) ACCELERATED REAMERS

Since the reamers 840 at station #8 must pass from one end of the articles 835 clear through their full length and out the other end during the same time that the other above mentioned tools are only moving and cutting about $\frac{1}{4}$ of the same length, a pair of accelerating mechanisms 860 may be mounted on the tool device 800 to advance these reamers at a rate over seven times that of the above mentioned drills. In order to provide for this increased accelerating motion for the high speed reamers 840, a special hydraulic cylinder 870 may be mounted on the device 800 as shown in Fig. 27 for each reaming station. The cylinders 870 may advance the high speed reamer tools 840 through guiding sleeves 871, and after they have reached depth and projected completely through the articles 835, as shown at station #8 in Fig. 25, they may be retracted, all of which may be accomplished under the control of limit switches 872 and 873 described later and 60 operated by cams 874 and 875 which travel with the accelerating reamers 840 (see Figs. 27 and 32). It has been found advantageous to have its spiral cutting edges on the reamers 840 formed so that the chips will be thrown outwardly ahead of the reamer, to lessen the 70

possibility of having chips and shavings jam up behind the reamer between its driving head and the end of the article 850.

(c) ARTICLE EJECTORS

The next and final stage or station #9 is the station in which chucks 609 mounted in the trunnion wheel 500 are operated upon by the unclamping hydraulic cylinders 632 and 633 to release the completed articles or wrist pins 850, so that it may be pushed out by ejector bars 890, whose accelerated motion may be produced by a multiplying lever connection as shown in Fig. 28. This connection comprises a lever 891 pivoted intermediate of its ends on a pivot 892 mounted on the movable cutting head device 800. One of the ends 893 of the lever 891 is pivotally attached to a rod 894 which rod may be resiliently attached to a stationary bracket 895 mounted on the base portion 104 of the machine, and the other end 896 of the lever is pivotally attached to a pair of ejector rods 890 which may be guided through brackets 897 on the head 804 of movable tool device 800. The action of the lever 891 may be against one or more springs, such as spring 898 on rod 894, to prevent jamming of the mechanism. Accordingly, since the movable pivot 892 is intermediate a fixed end pivot 893 and the other end pivot 896, any movement of the pivot 892 will be multiplied in the motion of the pivot 896, which thus moves the ejector bars 890 over a greater distance than the device 800 travels, enabling the ejector bars to completely pass through the chucks 609 and discharge any articles in them into the channels 166.

The next station is 180° from the initial starting point on the trunnion wheel 500 and comprises another station #1 but of the second group of stations, as shown on the bottom of the schematic diagram of Fig. 24. Now the above operations are repeated until a complete 360° rotation of the trunnion wheel 500 has occurred, during which time two pairs of wrist pins 850 have been completed from the ends of each of four bars 155 of stock, not to mention the 32 other pieces in the machine in different stages of completion. Accordingly, each revolution of the trunnion wheel when fully loaded, completes 36 wrist pins.

The multiple operations and drilling stations have been so calculated that the time required for making each of the cuts at each of the work stations is substantially the same, so that no time will be lost in waiting for one of the cutting operations to be completed while another has already been completed. Thus, many types of machining operations, such as sawing, drilling, chamfering, facing, reaming, and the like may be performed in a machine of this type, in which the cutting stages are divided in time so that equal amounts of cutting may be proportioned over each one of the stations employed in the machine.

E. CONTROL SYSTEMS

9. Hydraulic systems

For clarity of description and illustration, the many hydraulic conduits, valves and controls have been omitted from the previous figures of the drawings, which are now shown schematically in Figs. 30, 31, 32 and 33 for each of the seven separate hydraulic systems employed in the machine. Since the hydraulic systems for moving and controlling both of the saw mechanisms 700 and 701 and both of the tool devices 800 and 801 are separate and substantially identical, only one exemplary system therefore is shown in Fig. 33.

Considering first the most simple hydraulic system shown in Fig. 33, the hydraulic liquid from reservoir or tank (T) 900 may be kept under pressure by a pump 901 which may correspond to any one of the pumps 172, 173, 182 or 183 shown in Fig. 1, driven by a corresponding motor 902, corresponding to any one of the motors 170, 171, 180 or 181 in Fig. 1. Connected to the output of the pump 901 there may be a pressure gauge (G) 903

and a valve mechanism 904, which comprises a four-way valve operated alternately by the opposing electromagnets or solenoids (S) 905 and 906, the outputs of which valve mechanism 904 are connected to the opposite sides of the piston in a cylinder 907, corresponding to any one of the hydraulic cylinders 174, 175, 742 or 743 in Fig. 1. An additional valve 909 may be operated by a single spring returned solenoid 910 to connect an other and less volume output from another pump within pump 901 to the input of the cylinder 907 during the advance of the piston, which valve 909 may be controlled by the middle limit switch 911 of the three limit switches 911, 912 and 913 operated by the position of the piston 908. The limit switches 912 and 913 are located nearest the ends of the stroke of the piston 908, and may control corresponding solenoids 905 and 906, while the limit switch 911 may be located nearer the piston advance end of the piston stroke, so that the piston may advance its cutting tools quickly into their initial cutting position and then slowly while they are performing their cutting operations. The liquid return pipes to the tank 900 are only suggested by dotted lines to avoid confusion.

In cooperation with the cutting tools there is provided a separate hydraulic system shown in Fig. 32 for the hydraulic cylinders 870 on each side, or in each group of stations, to operate the accelerated reamer mechanisms 860 mounted on the movable tool device 800 which itself is moved according to the hydraulic system shown in Fig. 33. Here again in this circuit of Fig. 32 is provided a tank (T), which may be the same or a different source of supply for the hydraulic liquid than tank 900 in Fig. 33, and a pump 195 operated by motor 194 which supplies pressure through a four-way valve 915 (similar to valve 904) which may be controlled by solenoids (S) 916 and 917, to either move both of the pistons 870 forwardly or to move both of them rearwardly, the limits of which movements may be controlled by the limit switches 872 and 873, respectively. Both of the advance feeder pipes to cylinders 870 may be connected through flow control devices 918 to control the rate of motion for their pistons.

The other two hydraulic systems pressured by motor pump units 190, 192 and 191, 193, are for the several other and smaller hydraulic cylinders in the machine, and are shown in Figs. 30 and 31, respectively. These other hydraulic cylinders are divided between these two systems so that in most cases when two devices are to be operated at the same time, they will be operated in separate systems, so as to prevent loss of hydraulic pressure on a holding function of one or more cylinders when another cylinder is thereafter energized.

In the circuits of the hydraulic system shown in Fig. 30, there is also provided a tank (T) to which the outlets of each one of the cylinders are returned (as shown in dotted lines in all the Figs. 30, 31, 32, 33, connected to each of the valves), as well as a gauge (G) in the main line to indicate the pressure produced by the pump 192. Each of the cylinders may be operated by electromagnetic valves, with the valves 920, 921, 922, 923, 924 and 925 each operated by one spring return solenoid (S) and with valve 926 for the stock stops 710 and 711 operated by a pair of opposing solenoids (S). The shot pin device comprises three cylinders 585 and 586, which radially lock one of the side plates to the trunnion wheel and cylinder 587 which radially locks the other side plate to the trunnion wheel 500, all three of which cylinders may be operated simultaneously by one valve 920 and one limit switch 590. One of the fixture chuck clamping devices is operated by cylinder 631 and the valve 921 which may be controlled by a limit switch 931 (see Fig. 13). The magazine feed devices arranged in two pairs 209 and 201, one pair for each side of the machine, and one piston for each of the bars 150, and all four cylinders 220 and 221 may be controlled in parallel by the spring return valve 922. The roll feeders

300 and 301 comprise four cylinders 340 and 341 also, all of which may be controlled in parallel by a single valve 923, similar to those of the magazine feeder. The right and left side grip feeders, namely one for each of the four bars 153 fed into the machine, are usually operated in unison and may be controlled by spring actuated valves 924 and 925 for separate pairs of cylinders 410 and 411 on each side of the machine. The stock stops, which are advanced only during the cropping cycle, as are the magazine feeders and roll feeders, comprise separate pairs of cylinders 712 and 713, one cylinder for each bar of stock fed into the machine, and all four also may be controlled in parallel by a single valve 926.

Referring now to the systems of Fig. 31, there is the other fixture chuck clamp mechanism 630 for the other group of operating stations, the hydraulic cylinder of which may be controlled by a spring return hydraulic valve 930 and limit switch 932. The grip feeder steady locks comprise a pair of cylinders 417, one for the grip feeder on each side of the machine, which may be controlled by a spring operated valve 937, but this device is operated only during the crop cycle of the machine. Another spring operated solenoid valve 940 may control the cylinders 632 and 633 for unclamping the fixtures, one cylinder for each group of stations. The other pair of cylinders 414 and 415, one for each group of stations and each side of the machine, are provided for moving the grip feeder mechanisms 400 and 401, each of which cylinders may be controlled by separate double solenoid valves 941 and 942. Each of these cylinders 414 and 415, however, is provided with an additional piston head 464 and 465, respectively, which control the further retraction of each piston at the end of each bar 155 before the start of the next crop cycle. This further retraction operation may be controlled by the counter 1470 (see Fig. 35) which determines when to operate the spring return solenoid valve 944, located in the pressure pipe from the pump 193 after a check valve 945, to relieve the pressure normally applied on the additional piston heads 464 and 465 to keep them forward. With this pressure relieved or exhausted, the normal retraction pressure applied to cylinders 414 and 415 through valves 941 and 942 will move their pistons back farther than normally, because there is now no obstructing pressure on the heads 464 and 465. This additional retraction of the pistons at the end of each bar 155 permits short stub rear ends from the bars 155 to be dropped out and down onto the shaker conveyor 160 at the bottom of the machine, and not remain in the grip feeder where they might cause jamming. With the pressure against pistons 464 and 465, these pistons act as back stops for the pistons of the grip feeder cylinders 414 and 415, and accordingly can be used to determine the length of the blanks 155 fed into the chucks 600.

10. Electrically controlled sequence operations

(a) CROP CYCLE

The sequence of automatic and semi-automatic operations of the control devices, which comprise numerous solenoids, relays, limit switches, electric timers, and like electric equipment, most of which is located in cabinets 196 and 197 in Fig. 1, are schematically shown in the block diagram in Figs. 34 and 35. In Fig. 34 only the crop cycle operation of the machine herein described is shown, in which the solid lines connecting the blocks indicate the normally used manual or semi-automatic sequence of operation of this cycle in which push buttons or switches aligned in the square blocks along the left-hand side of Fig. 34 are used to start each major step of the crop cycle. However, if part or all of this crop cycle is to be controlled automatically, the dotted connecting lines, which by-pass these push buttons, also should be followed.

Describing the operation of the crop cycle it will be assumed that the machine is empty or just being started up

for a new job and a plurality of equal length bars 150 have been placed in the magazine racks 156, 157 and 158 (see Figs. 3, 4 and 5). First the start motor switch 1000 is closed to start all of the electrical motors employed in the machine including both the tool motors and those for the pumps in the hydraulic system, except the index-motor 551 and preferably also the roll feed motors 321, which specific motors are only energized intermittently by the present circuit.

If this cycle is not fully automatic the next button which is to be pressed is switch 1200 which starts the magazine feeder to operate the solenoid valve 922 to move the pistons in all of the magazine feed hydraulic cylinders 220 and 221 simultaneously, which permits one bar from each of the four rows of bars in the racks to be rolled onto the idle rollers 302 and 303 of the roller feeders 300 and 301. This circuit 1210 remains energized until all four of the bars are in contact with the rollers 302 and 303, at which time one or more bar actuated switches 1220 through circuit 1230 releases the circuit 1210 by deenergizing the spring returned solenoid connected to valve 922, so that the magazine feeder cylinders 220 and 221 are hydraulically returned to the positions shown in Fig. 5.

If the cycle is still not in automatic control, the next button which is to be pressed is the indexing switch 1500. This switch controls circuit 1510 to operate the solenoid valve 920 to remove the shot pins from the trunnion wheel 500 by operation of all of the mechanisms 585, 586 and 587 simultaneously and start a timer 1520 to insure sufficient time for all of the shot pins to be retracted, after which the timer starts the indexing motor 551 to rotate the trunnion wheel until its limit switches 565, 566, 567 and/or 575 in circuit 1530 stop the motor 551 at its proper place which then controls the circuit 1540 to deenergize the solenoid of valve 920 so that all three of the shot pins are again placed in the trunnion wheel to lock it from rotation during the present working or herein crop cycle. To insure sufficient time for the reinsertion of the shot pins, the limit switch 590 operated by one of the pins may be operated before circuit 1610 is energized to operate the spring returned valve 940 to unclamp the fixture chuck clamps at the last station #9 of each group of stations. To this pin unclamping circuit is connected a timer 1620, which timer controls circuit 1630 to deenergize the solenoid of the valve 940 to retract the piston of the unclamping cylinders 632 and 633.

If the circuit still is not fully automatic, the next button to be pushed is that for the grip feeder switch 1400, which simultaneously energizes circuit 1710 to advance to four stock stops and circuit 1410 to advance the two grip feeders 400 and 401. Energization of the circuit 1710 energized the solenoid 926 to advance all four of the stock stops 710 and 711 into the dotted line positions shown in Fig. 11, to prepare for the cropping, by the saws 704 and 705, of the stub ends of the new bars which will soon be fed towards these stops adjacent the trunnion wheel 500. Energization of the advance grip feeder circuit 1410 operates the solenoid valves 441 and 442 simultaneously, which moves pistons in cylinders 414 and 415 until they contact their forward limit switches 412, to start a timer 1420 to insure their full forward movement before starting simultaneously, three more circuits, namely, the locking circuit 1430 for the grip feeder, circuit 1440 to open the grip feeder clamps, and circuit 1450 to operate the fixture chuck clamps. The circuit 1430 operates the spring returned solenoid valve 937 to operate the cylinders 417 to the slides of the grip feeders locking them in their forward position. The circuit 1440 energizes the solenoids of valves 924 and 925 to retract simultaneously the pistons in each of the four cylinders 410 and 411 to open the clamp jaws 428 and 429 of the grip feeders to receive the bars 155 when they are fed through openings 424 and 425 by the roll feeders 300 and 301. The circuit 1450 energizes the solenoids of valves

921 and 930 to operate the cylinders 631 and 630, respectively, to close the fixture chuck clamps at each of the first operating stations #1 at the trunnion wheel, but these clamps do not close sufficiently tight to clamp the stock stops 710 and 711 which extend through these particular chucks at this time. These two chucks at the crop cycle remain empty for one complete group of working operations to account for the cropping of the stub ends of the new bars 155.

If still manual operation is continued, the next switch to be operated is the roll feeder switch 1300, which then operates the circuit 1310 to energize the spring returned solenoid of valve 923 to operate simultaneously the four control roll feeder hydraulic cylinders 340 and 341, and also simultaneously start the roll feed motors 321, which then starts a timer 1320 to insure sufficient time for the bars to move into contact with the advanced stock stops 710 and 711. After this time has expired, the circuit 1460 is operated to deenergize the solenoids of valves 924 and 925 of the grip feeder clamps, so that the pistons of cylinders 410 and 411 will be advanced to grip the ends of the bars 155, just fed through the openings 424 and 425 to abut against the extended stock stops 710 and 711. These grip feeders maintain this clamping of the bars during this crop cycle until after the stub ends have been cropped or sawed off by the saws 704 and 705.

If this circuit is now automatic a timer 1465 may be employed from the circuit 1460 to insure that the grip feeder clamps have completely closed on the bars, before the next circuits are operated. However, if the operation is still manually actuated, the next button to be pushed is that of the advanced tool switch 1700. This switch 1700 now simultaneously starts three more circuits, namely the retract stock stops circuit 1770 by operating valve 926 away from its position shown in Fig. 30, the advance saws circuit 1780, and the advance drill heads circuit 1810. The advance saw circuit 1780 operates both valves 904 and then both valves 909 to advance the saws 704 and 705 first into position and then through cutting under the control of limit switches 1782, as switch 911 shown in Fig. 33, to completely cut off or crop the stub front ends of the bars 155. Simultaneously with this sawing, there is energized the advance drill head circuit 1810 which operates another pair of valves, similar to valves 904 and 909 in Fig. 33, for advancing the drill heads 800 and 801 into cutting positions and then through cutting under the control of a limit switch 1811 as switch 911. As the saws and the drills advance they operate their limit switches 1782 and 1811 and while the saws are passing to their end limit switches 1785 (similar to switch 912 in Fig. 33), the advance reamer circuit 1820 is energized to energize the solenoid 917 to operate valve 915 in Fig. 32 to speed up and increase the movement of the reamers 840 during the cutting period of the saws and drills. As soon as the saws reach depth they operate their limit switches 1785 to energize their retraction circuit 1790 to energize the other solenoids on valves 904 and deenergize the solenoid for valve 909 to return the saw mechanisms to the full line positions shown in Fig. 3 at which time the rear limit switches 1795, similar to switch 913 in Fig. 33, are operated to indicate the sawing operation and retractions have been completed.

The operation of the limit switch 1785 also energizes three more circuits, namely circuit 1435 to unlock the grip feeders, circuit 1440 to open the grip feeder clamps, and circuit 1480 to retract the fixture clamp cylinders preparatory to the next indexing operation. The circuits 1435 and 1440 release the bars 155, so the grip feeders 400 and 401 may be retracted for feeding in a regular article or blank length into the chucks 600 during the next cycle. The opening of the grip feeders 1440 by energizing the solenoids of valves 924 and 925 may operate a timer 1485 to insure they completely open the jaws 428 and 429 before energizing the circuit 1490 to retract the grip feeders 400 and 401 by operation of the solenoid valves 941 and

942. Near their retracted positions they operate limit switches 1492 which may start a timer 1495 to insure complete retraction before the grip feeder clamp circuit 1460 is again operated to deenergize the solenoids of valves 924 and 925 to again clamp the bars 155 between the jaws 426, 427, 428 and 429, ready for advancing the grip feeders of bars 155 during the first part of the next cycle described in the next sub-chapter.

The advancing reamers when they approach depth operate limit switches 872, which may start a timer 1825 which insures the reaching of depth before energizing the retract reamers circuit 1830 which energizes solenoid 916 to operate valve 915 back away from the position shown in Fig. 32 to retract the reamers. When the reamers have been retracted they operate limit switches 873 to indicate they have completed their cycle of operation. As soon as the drill heads 800 and 801 approach depth they operate limit switches 1812 to start a timer 1815 to insure their depth, and to energize the retract drill heads circuit 1840 to operate their valves, similar to valves 904 and 909 as described for the saw mechanisms above, after which retraction their rear limit switches 1845 (similar to switch 913) are operated to indicate the devices 800 and 801 are in their full line positions shown in Figs. 1 and 2.

The discharge of the completed pins from station #9 is mechanically accomplished by the ejectors 890 (see Fig. 28) but has no effect if the machine is empty as it has been assumed above. This function is indicated by the block 1816 attached to the circuit 1810 since it operates simultaneously with this circuit.

If the system is now to be put into automatic operation, the automatic switch 1900 is operated or may be operated together with the advance tool switch 1700, so that as soon as the limit switches 1845, 873 and 1795 have been operated by the retraction of the reamers, drill heads, and saws, a circuit will be established through the dotted line 1901 by-passing the indexing switch 1500 to energize the pull shot pins circuit 1510 and motor 551, which then will continue through repeated automatic machining cycles as shown in Fig. 35.

The release of the roll feeder levers or retraction of pistons 342 and 343 clamping the bars 153 or 155 in the roll feeders, is not operated until the first of the following automatic machining cycle, by the connection 1330 from the pull shot pins circuit 1510 to operate release roll feeder lever circuit 1340, because there is no other clamp on these bars during retraction of the grip feeders 400 and 401 during the crop cycle of operation, as there is by the chucks 600 during the automatic machining cycle described in connection with Fig. 35. Since this operation, however, is only connected with the end of each crop cycle of operation, it has been disclosed in Fig. 34 as if connection 1901 had been completed. This sequence insures the holding of the bars 155 throughout the retraction and reclamping of the bars by the grip feeders 400 and 401.

There also may be provided in this circuit a safety switch 2000 which is directly connected to the retraction circuits 1840, 1830 and 1790 for the drill heads, reamers and saws, respectively, so that any time any part gets jammed, this switch 2000 may be manually operated to retract these three cutting devices, regardless of their position in the machine, freeing the ends of all the parts being machined around the trunnion wheel 500.

(b) AUTOMATIC MACHINING CYCLE

According to the circuit in Fig. 35, the normal automatic machining cycle sequence of operation is in full lines connecting the block circuits, which circuits are ordinarily instigated by the pushing of the automatic switch 1900 near or at the end of the crop cycle as described above. The manual operation of this circuit in Fig. 35, is therefore shown in dotted lines, with those portions of the circuit both in solid and dotted lines being disconnected when only the system is being manually

operated. The arrangement of the block circuits indicating the different parts of the apparatus in Fig. 35, is identical to that shown in Fig. 34, but only those block circuits are shown in Fig. 35 which take part in the automatic machining cycle which continues as long as the bars 155 last after which another circuit, namely, the counter 1470, is put into operation to shut off the device by opening the indexing switch 1500 through the connection 1425, or else also through the dotted connection 1426, to automatically connect with the magazine feeder 1210 to start and automatically operate the crop cycle.

Following through the automatic operation which is instigated by the closing of the indexing switch 1500, or of the automatic switch 1900, circuit 1510 is energized to pull the shot pins and index the trunnion wheel to the next station, and reinsert the shot pins, as previously described through circuit 1510, timer 1520, index motor 551, limit switch 1530 and circuit 1540, at the end of which the limit switch 590 indicates that the shot pins are again advanced into locking position.

After the indexing has been completed the limit switch 590, simultaneously energizes three separate circuits, namely circuit 1610 to unclamp pins in the fixture chucks 600 at stations #9, advance grip feeder circuit 1410, and the advance drill heads circuit 1810. As distinguished from the crop cycle system, the saws are not yet advanced but are done so later under the control of the operation of the grip feeders 400 and 401. When the grip feeders have advanced to operate their limit switches 412 and start the timer 1420, this timer then operates circuit 1450 to clamp the bar in the fixture chucks 600, after which the limit switches 931 and 932 are operated to start a timer 1455. The timer 1455 then after insuring the chucks are closed, operates two circuits simultaneously, namely: circuit 1440 for opening the grip feeder clamps and circuit 1780 to advance the saws. Since the blank length ends from the bars 155 have now been clamped into the chuck fixtures 600, the grip feeders 400 and 401 may now be released and retracted for the next indexing operation through the operation of circuits 1440 and 1490, timer 1485, limit switch 1492, timer 1495, and then reclamped through circuit 1460.

Now the saws may be advanced through operation of circuit 1780 to pass their limit switches 1782 to the second limit switches 1785, which then energizes two circuits, namely circuit 1790 to retract the saws, and circuit 1480 to retract the clamp fixture cylinders 630-631, respectively, so that the trunnion wheel 500 will be free to rotate when the next indexing operation is to start.

In the meantime the drill heads 800 and 801 have advanced under the control of circuit 1810 to operate limit switches 1811 to start the advance reamers circuit 1820 and then operate their second limit switch 1812 to start timer 1815 before operating their retract drill heads circuit 1840. The advanced reamers 860 operate their limit switch 872 to start timer 1825 to insure their full depth, and then to operate retract reamers circuit 1830.

As soon as all of the final rear limit switches 1845, 873 and 1795 have been operated, indicating that both drill heads, both reamers and both saw devices have reached their retracted positions, then all of these switches 1845, 873 and 1795 operate to complete a series circuit through connection 1901 to energize again the pull shot pins circuit 1510, and repeat the whole cycle again according to the solid lines just described.

If at any time it is desired to stop the automatic operation at the end of a cycle, the automatic switch 1900 may be opened, and then the manual switches 1500, 1400, 1700, may be normally operated to make connections according to the dotted lines from these switches to control the machining operations. Also the safety switch 2000 may be operated instantaneously and simultaneously to operate the retraction circuits 1840, 1830 and 1790 of the drills, reamers, and saws, respectively. In such event when the machine is stopped some time

5 1700 and automatic switch 1900.

In order to determine the end of the bars 155 or any bar 155, there may be provided an additional circuit through an additional limit switch or switches 470 and 471 connected from the outlet of the advanced feeder 10 circuit 1410, which switches are operated when the end of the bar or bars are detected, as shown in Fig. 4, to start a counter circuit 1470 which counts a predetermined number of blanks, corresponding to an equal number of reciprocations of the grip feeders 400 and 401, which may be cut between the location of said switches 470 and 471 and the saws 404 and 405. After this number has been counted a new connection is established for performing two functions: first, to further retract the grip feeders 400 and 401 by energizing circuit 1475 and the 15 20 solenoid to operate valve 944 to prevent pistons 464 and 465 from limiting the retraction of the pistons in cylinders 414 and 415, so that the final or new slug ends of the bars may freely drop onto the shaker conveyor 160; and second, to establish connection 1425 to stop immediate 25 repetition of the automatic machining cycle, by either opening the indexing switch 1500, or through an additional connection 1426 to automatically start the crop cycle of Fig. 34 to feed new bars 150 into the machine. The next advance of the grip feeder during the crop 30 35 cycle automatically deenergizes the solenoid of the valve 944 so that the pistons 464 and 465 again are advanced as rear limiting stops for normal reciprocation of the grip feeders 400 and 401.

The foregoing detailed description of an embodiment 35 of this invention for manufacturing or producing hollow wrist pins to proper lengths and inside dimensions from solid bars stock in one machine only, may be extended for a greater plurality of bars to be inserted simultaneously into different equally spaced work stations around 40 a larger continuous conveyor than the disclosed trunnion wheel 500, for producing a greater plurality of parts simultaneously, without departing from the principle of this invention. Also the machine of this invention is readily adaptable to the manufacture of other articles 45 from bars of stock besides wrist pins, for which different types as well as different numbers of working stations may be employed, that is rearrangement of the tools at the working stations, changing the dimensions of the clamps for different sizes of stock, etc. Furthermore, 50 the specific type of chuck employed on the conveyor, namely the trunnion wheel 500, has novelty and utility in other machines than the one herein described, because of its positive action and providing a clamping arrangement which does not have to be locked because of the 55 wedge of the threads and the jaws which do the clamping.

Although the above description has been directed to semiautomatic operation for bars of stock of all the same length, the circuits shown in Figs. 34 and 35 indicate how the machine of this invention may be operated fully automatically through both crop and machining cycles, or manually, for either bars of stock of the same or different lengths.

While there is described above the principles of this 60 invention in connection with specific apparatus, it is to be clearly understood that this description is made only by way of example and not as a limitation to the scope 65 of this invention.

What is claimed is:

1. A chuck comprising two pairs of jaws, one jaw 70 of each pair being C-shaped, a threaded shaft between said pair of jaws with one jaw of each pair being attached to a member, said member being threaded on said shaft, a pinion mounted on said shaft, a rack means for rotating said pinion and said shaft, means to prevent the rotation of said member relative to said shaft whereby said jaws

attached to said member are moved as a wedge across the open ends of said C-shaped jaws when said shaft is rotated, and means for longitudinally moving said rack means.

2. A chuck according to claim 2 including a pair of opposing hydraulic motors, one for abutting each end of said rack means alternately.

3. A chuck means according to claim 1 wherein one of said jaws of each pair comprises a pair of axially spaced C-shaped members with a pair of angularly spaced inwardly projecting teeth inside each C-member.

4. A chuck for cylindrical articles comprising: a pair of cooperating jaws, one of said pair of jaws comprising two parallelly aligned axially spaced C-shaped jaw members or more than 180° in angular extent, each of said C-shaped members having a pair of inwardly extending angularly spaced teeth, the other jaw at least partly bridging the space between said C-shaped members and having a flat wedging surface cooperating with the open ends of said C-shaped members, the perpendicular plane to said wedging surface through the axis of said cylindrical article being clamped passing between said teeth on each of said C-shaped members, and means for moving said wedging surface relative to said open ends of said C-shaped members.

5. A chuck for a pair of cylindrical articles comprising: two pairs of parallel spaced co-operating jaws, one and the outer jaw of each of said pairs of jaws comprising two parallelly aligned axially spaced C-shaped jaw members of more than 180° in angular extent, the other and inner jaw of each of said pairs of jaws comprising a single wedged shaped member between said outer jaws and having two opposing faces, each of said faces at least partly bridging the space between said C-shaped members of its corresponding outer jaw with the perpendicular planes to said faces passing through the respective axes of said pair of cylindrical articles being clamped in said chuck, and means for moving said wedge shaped member relative to said open ends of said C-shaped members.

6. A conveyor for moving objects successively to a plurality of stations; a clamping means mounted on said conveyor, said clamping means comprising: a pair of co-operating jaws, one of said jaws being a C-shaped member and the other of said jaws being a wedging member, a threaded shaft, one of said jaw members being threaded on said shaft, a pinion mounted on said shaft, a rack means for rotating said pinion to move said one of said jaw members along said shaft into and out of

jaw clamping position; and means to move said conveyor from station to station; means at one station to operate said rack means into jaw clamping position; and means at another station to operate said rack means out of jaw clamping position.

7. A conveyor according to claim 6 wherein both said means for operating said rack means comprise a reciprocating hydraulic cylinder for abutting opposite ends of said rack means.

- 10 8. A conveyor for moving a pair of cylindrical objects successively to a plurality of stations; a clamping means mounted on said conveyor, said clamping means comprising: two pairs of parallel spaced co-operating jaws, one and the outer jaw of each of said pairs of jaws comprising two parallelly aligned axially spaced C-shaped jaw members of more than 180° in angular extent, the other and inner jaw of each of said pairs of jaws comprising a single wedge-shaped member between said outer jaws and having two opposed faces, each of said faces at least partly bridging the space between said C-shaped members of its corresponding outer jaw with the perpendicular planes of said faces passing through the respective axis of said pair of cylindrical objects being clamped therein, means for moving said wedge-shaped member 20 relative to said open ends of said C-shaped members; means to move said conveyor from station to station; means at one station to operate said moving means into jaw clamping position; and means at another station to operate said moving means out of jaw clamping position.
- 25 9. A conveyor according to claim 8 wherein said means for moving said wedge-shaped member comprises a threaded shaft, said wedge-shaped member being threaded on said shaft, a pinion mounted on said shaft, and a rack means for rotating said pinion to move said member 30 along said shaft into and out of jaw clamping position, said rack means being operated by said operating means at said one and said other stations.
